(57) **CLAIM**

The ornamental design for an accessory mount, as shown and described.

DESCRIPTION

FIG. 1 is a top isometric view of an accessory mount, wherein the paddle actuator of the accessory mount is shown in a first position;

FIG. 2 is a bottom isometric view of the accessory mount shown in FIG. 1;

FIG. 3 is a top isometric view of the accessory mount shown in FIG. 1, wherein the paddle actuator of the accessory mount is shown in a second position;

FIG. 4 is a bottom isometric view of the accessory mount shown in FIG. 3;

FIG. 5 is a front side elevational view of the accessory mount shown in FIG. 3;

FIG. 6 is a right side elevational view of the accessory mount shown in FIG. 3;

FIG. 7 is a rear side elevational view of the accessory mount shown in FIG. 3;

FIG. 8 is a left side elevational view of the accessory mount shown in FIG. 3;

FIG. 9 is a top plan view of the accessory mount shown in FIG. 3; and,

FIG. 10 a bottom plan view of the accessory mount shown in FIG. 3.

The broken lines represent portions of the accessory mount that form no part of the claimed design.
